US00D803309S

(12) **United States Design Patent** (10) Patent No.: **US D803,309 S**
(45) Date of Patent: **** Nov. 21, 2017**

(54) **ELECTRONIC COPYING MACHINE**

(71) Applicant: **TOSHIBA TEC KABUSHIKI KAISHA**, Shinagawa-ku, Tokyo (JP)

(72) Inventors: **Keiichiro Takahashi**, Kawasaki Kanagawa (JP); **Hisaya Ishio**, Kawaguchi Saitama (JP)

(73) Assignee: **TOSHIBA TEC KABUSHIKI KAISHA**, Tokyo (JP)

(**) Term: **15 Years**

(21) Appl. No.: **29/529,967**

(22) Filed: **Jun. 11, 2015**

(30) **Foreign Application Priority Data**

Apr. 11, 2015 (JP) 2015-008263

(51) LOC (10) Cl. **16-03**

(57) **CLAIM**

The ornamental design for an electronic copying machine, as shown and described.

DESCRIPTION

FIG. 1 is a perspective view of a electronic copying machine showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken line showing in the drawings is included for the purpose of illustrating portions of the electronic copying machine and forms no part of the claimed design.

1 Claim, 7 Drawing Sheets
